DIAPER SUPPORT

Helen Booker Carter, Forest, Va.

Application October 17, 1946, Serial No. 703,910

3 Claims. (Cl. 2—112)

1

My invention relates to garment supports and, more particularly, to an improved diaper support. Heretofore, it has been the practice to support diapers by pinning or otherwise fastening the upper edge of the diaper, after folding, to the infant's shirt or waist. It has also been proposed to provide diaper supports comprising a waist portion, that is to say, a separate garment, adapted to fit over the infant's conventional undershirt, the diaper having diaper attaching means at the front, back and/or sides. While the prior suggested arrangements no doubt function for the intended purpose, they are open to many inherent objections. When the diaper is supported directly on the infant's under shirt, considerable difficulty is encountered in properly positioning the diaper with respect to the lower portion of the shirt and in manipulating the pins to avoid injury and discomfort to the infant. Even though a suitable support may eventually be obtained, care must be exercised during the application of the diaper to prevent undue restraint in the vicinity of the infant's stomach, and to eliminate sagging or drooping at areas intermediate the points at which the diaper is pinned to the undershirt. Support devices of the type wherein a separate garment is used having diaper attaching means in the form of buttons, pins and the like, associated with the lower portion of the garment, do not satisfactorily support the diaper for the reason that the positions of the points of support cause sagging, due to uneven pull exerted at the front or rear of the garment. Devices of this character are also difficult to position on an infant, since they usually are provided with comparatively small neck and arm openings.

The improved diaper support of the present invention comprises essentially, a buttonless one-piece halter-type body, having an enlarged neck portion and open sides, to provide unrestricted arm openings. The diaper is supported through the medium of elastically connected tabs arranged at the sides of the body portion, the front and back panels together with means for attaching the tabs, being designed to maintain the tabs in a substantially flat position at the sides of the support.

An object of my invention is to provide an improved diaper support.

Another object of my invention is to provide a diaper support having improved means for attaching and properly supporting a diaper in desired position.

A further object of my invention is to provide a diaper support having a comparatively large neck opening and unrestricted arm openings, whereby the support may be quickly and easily positioned on an infant.

Still another object of my invention is to pro-

2

vide a buttonless diaper support, having a body portion formed from a single blank of fabric.

Yet another object of my invention is to provide a diaper support having diaper attaching tabs elastically connected thereto in the vicinity of the side of the support.

A still further object of my invention is to provide a diaper support having symmetrically shaped front and back panels designed to provide uniform distribution of pull or tension throughout the support, after the diaper has been attached.

With these and other objects in view, which may be incident to my improvements, the invention consists in the parts and combinations to be hereinafter set forth and claimed, with the understanding that the several necessary elements, comprising my invention, may be varied in construction, proportions and arrangements, without departing from the spirit and scope of the appended claims.

In order to make my invention more clearly understood, I have shown in the accompanying drawing means for carrying the same into practical effect, without limiting the improvements in their useful applications to the particular constructions, which for the purpose of explanation, have been made the subject of illustration.

In the drawings:

Fig. 1 is a plan view of the body portion of diaper support.

Fig. 2 is a perspective front view of the diaper support showing the arrangement of the diaper attaching tabs.

Fig. 3 is a perspective side view of the diaper support shown in Fig. 2; and

Fig. 4 is a detail view of a diaper attaching tab.

Referring to the drawings and more particularly to Fig. 1, the body portion 1 of the diaper support is formed with a substantially elliptical-shaped cut-out portion 2, centrally thereof, the major axis of the ellipse extending lengthwise of the body. The end edges 3 of the body portion are arcuate shaped and the sides 4 are curvilinear, as shown. The purpose of this arrangement, as will be described more fully hereinafter, is to properly position the tab support members 5 and to distribute the pull or tension uniformly of the body portion after a diaper has been attached to the support.

As will be seen in Fig. 2, the support is assembled by folding the body portion 1 along a median line, thus providing symmetrically shaped front and back panels 6 and 7. It will be noted that the semi-elliptical-shaped portions define an enlarged neck opening 8 having shoulder pieces 9 at opposite sides thereof, and that the free edges 4 provide unrestricted arm

openings 10. Elastically attached to support members 5 at the lower corners of the panels are a pair of diaper attaching tabs 11, which, by reason of the curvature of the sides of the panel, together with the elastic connecting tapes 12, maintain the tabs in desired flat position at the side of the support, as shown in Fig. 3. Correct positioning of these tabs at the sides of the panels is one of the important features of my improved diaper support since they are easily accessible for pinning purposes, and after the diaper has been attached, even distribution of pull or tension is obtained, thus preventing the shoulder pieces from sliding outwardly off the infant's shoulders, while otherwise permitting freedom of movement.

Referring to Fig. 4, it will be noted that the elastic tape 12, by means of which the tab 11 is elastically connected to opposite lower corners of the panel, is arranged in substantially V-form, the closed portion 13 thereof being stitched or otherwise fastened to the tab. In connection with the V-arrangement of the connecting tapes, it will be seen that the arms partially overlap as at 14, and that the free ends are attached to the tab support members 5 (Fig. 2) at one of the lower corners of the support. By means of this arrangement of the parts, longitudinal stretch is permitted between the support and the tabs to which the diapers are attached, thus allowing desired freedom of movement.

Each of the tabs 11 (Fig. 4) is provided with a diaper fastening means, comprising a conventional safety pin 15, attached to one end of a suitable tape 16, the opposite end of the tape being permanently attached to a corner of the tab, as shown at 17. The fastening means may thus be conveniently located when required, and since it is permanently attached to the tab, it cannot become mislaid or accidentally lost in the infant's bed clothes or other garments during the time a diaper is being changed.

When it is desired to position the diaper support on an infant, it is only necessary to separate the panels 6 and 7 and slip the support over the infant's head. Due to the elliptical shape of the neck portion, an enlarged opening is readily formed by pulling outwardly on the shoulder pieces 9. The unrestricted arm openings 10 permit the infant's arms to move therethrough with ease and minimum effort.

It will be appreciated that in lieu of making the body portion of the diaper support from a single blank fabric, as described herein, that duplicate blanks can be cut to provide double thickness of material; the blanks being sewed and suitably bound along their marginal edges. The present invention also comprehends the use of different types of material for the body portion. For example, the fabric may, if desired, be of wool. In which case the support can, at certain seasons of the year, be used as a substitute for the infant's undershirt.

While I have shown and described the preferred embodiment of my invention, I wish it to be understood that I do not confine myself to the precise details of construction herein set forth, by way of illustration, as it is apparent that many changes and variations may be made therein, by those skilled in the art, without departing from the spirit of the invention or exceeding the scope of the appended claims.

I claim:

1. In a diaper support of the character described comprising symmetrically shaped front

and back panels, each of said panels having a substantially semi-elliptical shaped cut-out portion at the top and centrally of the panel, said portions defining an enlarged neck opening having shoulder pieces at opposite sides thereof, the adjacent side edges of the panels being spaced from one another and providing unrestricted arm openings, the lower edge of each panel being arcuate shaped and the side edges thereof being curvilinear, whereby to form a pair of integral tab support members of gradually reduced width at the opposite sides of the diaper support in the vicinity of the lower corners of the panels, means to elastically connect a diaper support tab to each pair of said support members comprising a V-shaped elastic tape having its free ends attached to the corners of the panels, and a diaper support tab attached to its closed portion.

2. In a diaper support of the character described comprising, a body portion formed from a single blank fabric having a substantially elliptical shaped cut-out portion centrally thereof, the body portion being folded upon itself along a line median of its ends, forming symmetrically shaped front and back panels, the semi-elliptical shaped portions of the panels defining an enlarged neck opening having shoulder pieces at opposite sides thereof, the adjacent side edges of the panels providing unrestricted arm openings, the lower edge of each panel being arcuate shaped and the side edges thereof being curvilinear, whereby to form a pair of integral tab support members of gradually reduced width at the opposite sides of the diaper support in the vicinity of the lower corners of the panels, means to elastically connect a diaper support tab to each pair of said support members comprising a V-shaped elastic tape having its free ends attached to the corners of the panels, and a diaper support tab attached to its closed portion.

3. In a diaper support of the character described comprising symmetrically shaped front and back panels, each of said panels having a substantially semi-elliptical shaped cut-out portion at the top and centrally of the panel, said portions defining an enlarged neck opening having shoulder pieces at opposite sides thereof, the adjacent side edges of the panels being spaced from one another and providing unrestricted arm openings, the lower edge of each panel being arcuate shaped and the side edges thereof being curvilinear, whereby to form a pair of integral tab support members of gradually reduced width at the opposite sides of the diaper support in the vicinity of the lower corners of the panels, means to elastically connect a diaper support tab to each pair of said support members comprising a tape having its free ends attached to adjacent corners of said panels, and a diaper support tab secured to the tape.
